UNITED STATES PATENT OFFICE.

JOHN BENKO, OF NEW YORK, N. Y.

DESIGN FOR A PICTURE-FRAME.

52,017.

Specification for Design.

Patented May 7, 1918.

Application filed December 8, 1917. Serial No. 206,349. Term of patent 3½ years.

To all whom it may concern:

Be it known that I, JOHN BENKO, a citizen of the United States, residing at New York, in the county of New York and State of New York, have invented a new, original, and ornamental Design for Picture-Frames, of which the following is a specification, reference being had to the accompanying drawing, forming a part thereof.

The Figures 1 and 2 are, respectively, a plan view of a picture frame and a side view thereof, showing my new design.

I claim:

The ornamental design for a picture-frame, as shown.

JOHN BENKO.
